UNITED STATES PATENT OFFICE.

WILLIAM H. PAINE, OF BROOKLYN, NEW YORK.

ROLLER-GRIP FOR CABLE RAILWAYS.

SPECIFICATION forming part of Letters Patent No. 296,605, dated April 8, 1884.

Application filed August 31, 1883. (No model.)

To all whom it may concern:

Be it known that I, WILLIAM HENRY PAINE, a citizen of the United States, residing at Brooklyn, in the State of New York, have invented certain new and useful Improvements in Grips for Cable Railways, of which the following is a specification.

My invention relates to an improvement in roller-grips for cable railways in which the gripping-rollers, when brought in contact with the rope, run thereon without friction, and are gradually locked to start the car, the grip-rollers continuing to turn until the car is in full motion at the same speed as the cable. By this means the car is started gradually without jerking, and friction between the rope and grip is avoided, the friction being wholly between the grip-rollers and the locking mechanism, by which their rotation is gradually retarded during the starting of the car. Letters Patent No. 173,329, granted to me on the 8th day of February, 1876, describe a device for accomplishing this purpose, and my present invention relates to improvements in the mode of mounting, operating, and locking the gripping wheels or rollers.

In the accompanying drawings, Figure 1 is a plan of the apparatus. Fig. 2 is a side elevation, partly in section. Fig. 3 is an end elevation. Fig. 4 is a transverse section on the line 4-4, Fig. 1.

Horizontal gripping-rollers 1 1^a, with flanged or concaved peripheries, are each journaled between a pair of levers, 2 2^a, suspended from the bottom of the car in position to engage the cable 3.

Fulcrumed to the ends of the levers 2 is a lever, 4, pivoted at 5 to a block, 6, sliding on a connecting-bar, 7, which is bolted to the ends 40 of the levers 2^a. The sliding block 6 is formed with an internally-screw-threaded lug, 6^a, through which passes an adjusting-screw, 8, whose inner end revolves freely in a lug, 7^a, formed on the bar 7. The levers 2 2^a, carrying the grip-rollers, are by this means held at the proper distance asunder to engage or retain the rope, any wear being taken up by the adjustment of the screw 8. The end of the operating-lever 4 may be connected to an endless rope passing over drums at either end of the car, operated by the hand-brake windlass, as I have described in a contemporaneous ap-

plication; or the said lever may be adjusted by hand.

9^a are jointed locking-levers fulcrumed to 55 the levers 2 2^a at 10^a, respectively, and carrying shoes 9^b 9^c, bearing outward against the inside of the rims of the grip-rollers 1 1^a, which are made dish-shaped, or with spokes on one face only, so as to permit the bent lever 9^a and the shoes 9^b 9^c to work within them, as illustrated in Fig. 2.

Bolted to the locking lever 9^a is a connecting-bar, 11, which carries a sliding block, 12, having a lug, 13, through which passes an adjusting-screw, 14, whose other end revolves in a lug, 11^a, on the lever 11, similarly to the adjusting-screw 8, already described in connection with the main levers 2 2^a.

Pivoted to the block 12 at 15^a is a bent lever, 15, whose shorter end is fulcrumed at 16^a to a similar bent lever, 16, whose shorter end is fulcrumed at 16^b to the other locking-lever, 9. The longer ends of the levers 15 16 are connected to the oppositely-moving portions 75 of an endless rope, 17, as fully set forth in the application above referred to. This construction is such that when the levers 15 16 are separated, as represented by dotted lines in Fig. 1, and the lever 4 in the position shown 80 in full lines, the cable 3 will be held between the rollers 1 1^a, while the latter run freely thereon, so as not to impart motion to the car. The first movement of the levers 15 16 toward one another will cause the locking-beams 9 9^a 85 to be quickly drawn together, thus placing the shoes 9^b 9^c in contact with the gripping-rollers 1 1^a, and a continuation of such movement, the fulcrum-points 15^a, 16^a, and 16^b having been brought nearer in line, will cause the 90 ends of said levers to press the locking-shoes in contact with the rollers with any necessary force.

The levers 2 2^a and locking-beams 9 9^a may be so adjusted by the screws 8 14, respectively, 95 that the foregoing result may be accomplished by very slight movements of the operating-levers.

To insure the stopping of the car or train of cars at the station, and avoid danger of 100 their being carried too far, the lever 4 projects beyond the side of the car, and is tripped at the proper distance from the end of the route by a projection from the bed of the

track, or other automatic means resulting in the certain and instantaneous detachment of the car from the cable.

In practice the levers 2 2^a are extended, as indicated at 2^x and 2^{ax}, to carry a second pair of gripping-rollers, similar to those shown at 1 1^a, the other extremities of the said levers being suspended from the car-body by lugs, similar to those shown at 18 on the levers 1 1^a, and connected by a similar bar, 7, lever 4, and their described accessories, or being pivoted to the body, as preferred. The members 2^a and 2^{ax} are connected by a knuckle-joint, x, bending freely outward, but inflexible in the other direction, so that the bar 7, lever 4, and their connections may draw the entire lever 2^x 2^{ax} toward the lever 2 2^a as one rigid member, but on the release of the connections 4 7 will instantly relieve the pressure of the rollers 1 1^a on the cable, the lever 2^a turning on the joint x and carrying with it the fulcrum 10^a of the locking-lever 9^a. The locking-shoes of the second pair of rollers are connected to duplicate locking-levers 9^x and 9^{ax}, the levers 9 and 9^a being jointed together at 16^b to the lever 16, and the levers 9^a and 9^{ax} being jointed together to a connecting-bar, 11, common to both, as clearly shown in Figs. 1 and 2.

Having thus described my invention, the following is what I claim as new therein and desire to secure by Letters Patent:

1. The combination, with a roller-grip for cable railways, of locking-shoes mounted on suitable beams, and bearing outward against the interior of the rim of the grip-roller, substantially as described.

2. In a roller-grip for cable railways, the combination of a pair of levers—one fulcrumed on the other—and locking-shoes moved by the said levers in opposite directions, substantially as set forth.

3. In a roller-grip for cable railways, the

combination, with the locking-shoes mounted on suitable levers, of a system of levers flexibly connecting said locking-levers, and having means for adjustment, as described. 45

4. In a grip for cable railways, the combination, with the gripping-rolls mounted in a pair of levers fulcrumed to the bottom of the car, of a pair of levers fulcrumed to the ends 50 of the aforesaid levers, and flexibly connected to each other, as and for the purpose set forth.

5. In a grip for cable railways, the combination, with a pair of levers carrying a pair of gripping-rollers, and flexibly connected together by a second pair of levers, of mechanism, substantially as described, for adjusting the levers carrying the rollers to and from each other, for the purposes set forth. 55

6. In a roller-grip for cable railways, the combination, with a pair of gripping-rolls mounted in a pair of levers, of a pair of levers fulcrumed to the ends of the aforesaid levers, and connected together through the medium of a sliding block mounted on one of the levers, and carrying an adjusting-screw having a fixed bearing in a lug on the other one of said levers, as and for the purpose specified. 65

7. In a device for gripping a moving rope or cable, a pair of gripping rolls or sheaves, and a locking device applied to one or more of the said gripping rolls or sheaves at a point or points nearer the moving rope or cable than the axles of the said gripping rolls or sheaves. 70 75

8. In a roller-grip for cable railways, means for applying locking-pressure to one or more of a pair of gripping rolls or sheaves at a point or points nearer their opposing surfaces than are their axles.

WILLIAM H. PAINE.
